UNITED STATES PATENT OFFICE.

EDWARD B. HESS, OF BROOKLYN, AND JOSEPH M. STOUGHTON, OF YONKERS, NEW YORK, ASSIGNEES, BY MESNE ASSIGNMENTS, TO ROYAL TYPEWRITER COMPANY, OF HOBOKEN, NEW JERSEY, A CORPORATION OF NEW JERSEY.

WRITING-MACHINE.

No. 830,478.

Specification of Letters Patent.

Patented Sept. 4, 1906.

Application filed October 3, 1902, Serial No. 125,809.

To all whom it may concern:

Be it known that we, EDWARD B. HESS, of the borough of Brooklyn, city of New York, and JOSEPH M. STOUGHTON, of Yonkers, county of Westchester, State of New York, citizens of the United States, have invented certain new and useful Improvements in Writing-Machines; of which the following is a specification.

- 10 This invention relates to devices for actuating type-bars of the general character disclosed in the United States patents of Edward B. Hess, No. 700,687, dated May 20, 1902; Edward B. Hess and Joseph M. Stoughton, No. 679,674, dated May 13, 1901; Edward B. Hess, No. 679,673, dated July 30, 1901; Edward B. Hess, No. 694,015, dated February 25, 1902, and United States application of Edward B. Hess, Serial No. 73,460, filed 20 August 27, 1901—that is to say, to a flexing type-bar-actuating connection connected at its rear end to the heel of the type-bar and at its front end to the frame, it being disposed in a direction fore and aft of the machine under the type-bar, which normally lies toward the front of the machine, and when flexed by power applied intermediate its ends and in rear of its point of attachment to the frame the angular relation of its parts on both sides 30 of its point of flexure is changed and the type-bar is thrown to the printing-point with an increasing velocity.

In the present structure, as in those disclosed in the patents and application mentioned, the part or member of the flexing connection located in front of the point of flexure rocks or moves about the point to which its front end is attached either with a truly pivotal movement, as shown in Patent No. 40 700,687, or otherwise, as shown in Patent No. 694,015. With such a flexing type-bar-actuating connection the initial depression of the flexing connection opposes a minimum resistance to the actuation of the finger-piece, and this resistance and correspondingly the velocity of the type-bar increases during the further depression of the finger-piece.

The present invention contemplates an organization by which the velocity of the type-bar toward the end of its movement to the printing-point is further accelerated, and to

accomplish this the part or member of the flexing connection in front of the point of flexure is either flexible throughout its length or capable of flexure at one or more points. In its initial depression the front member rocks or turns about its point of attachment to the frame, and thereafter and at a suitable time before the type-bar reaches the printing-point the front member is caused to flex at a point between its front and rear ends to thereby decrease the radius of the curve in which its rear end moves to effect an increased ratio of rise in the velocity of the type-bar. This may be conveniently accomplished by placing a stop or abutment under the flexing connection in front of or extending in front of the point to which its front end is attached.

A further feature of this invention is a special arrangement of spring for returning the type-bar to its position of rest combined with a flexible connection of the general character herein shown and disclosed in the patents above mentioned.

The accompanying drawings show merely detail views indicating a platen, type-bar, spring, and type-bar-actuating devices, and these devices may be embodied in complete machines constructed in the general way disclosed in the patents above mentioned or otherwise, as the designer of the machine may elect.

Figures 1, 2, 3, 4, 5, and 6 show, respectively, different or modified forms of the invention.

a is the platen; *b*, the type-bar to be pivoted in a segment located below the plane of the type-bar normally lying toward the front of the machine against the back-stop or rest *c*. To the heel of the type-bar under or in rear of its pivot is attached the rear member *d* of the flexing connection, shown as a link of wire hinged at its front end to the rear end of the front member *e*, whose forward end is attached to the frame.

In Figs. 1, 2, 3, and 4 the hinge-joint between the ends of the two members *d* *e* of the flexing connection is formed by flexibly attaching their ends to the lower end of a vertically-movable stem *f*, to which the finger-piece *g* is applied. As shown in Fig. 1, the front member of the flexing connection is

- composed of the two links *h i*, hinged together at *j*. Below this member and at or slightly in front of the joint *j* is placed an abutment *k*, which may be a rod, either straight or curved, according to the construction of the machine, extending between the side plates thereof or a piece carried by or forming part of a projection from the front part of the machine. During the initial depression of the finger-piece the entire member *e* descends until the outer portion *h* thereof is arrested by the abutment *k*, and thereafter only the front portion *i* continues to move on the continued depression of the finger-piece. The effect of arresting movement of the front part *h* is to reduce the radius of the curve in which the hinge-joint *l* moves, thereby materially increasing the rate of acceleration, while at the same time preserving the delicacy of touch of the finger-piece until the type-bar has been set in motion and made a substantial part of its excursion toward the printing-point. Experience has demonstrated that with a construction precisely as indicated in Fig. 1 no secondary resistance is noticeable when the front member of the connection strikes the abutment *k*, and the touch of the finger-piece is smooth and easy, although, of course, the resistance increases. The construction is the same in Fig. 2, except that the front member *e* is composed of three members united by two hinge-joints and two abutments *k m* are employed. In Fig. 3 the front member *e* is shown as a coiled spring which may, as indicated, be attached at its front end to the fixed piece or frame by soldering, as indicated at *n*. In this construction the abutment *k* produces substantially the same result. In Fig. 4 the front member *e* is shown as a chain, and the abutment is shown as a rearwardly-extending block or projection having a downwardly-curved face *o*.
- 45 In Fig. 5 the construction is the same as that of Fig. 1, except that the adjacent ends of the two members *d e* are attached to a link *p*, pivoted to the end of the stem *f*, this arrangement being that described and claimed 50 in the patent of Hess and Stoughton, No. 679,674, above named.
- In Fig. 6 the arrangement is the same as indicated in Fig. 1, except that instead of using a push-pin or stem *f* the flexing connection *d e* is actuated by a key-lever *q*, pivoted at its rear end and connected with the flexing connection at its joint *l* by a link *r*.
- In each of the figures the type-bar-return spring is shown as a relatively long coiled 55 spring lying between the type-bar and the rear member *d* of the flexing connection. It is connected at its rear end to the type-bar above or in front of the type-bar pivot and at its front end to any suitable piece, post, 60 or part of the frame. We have found this

arrangement of type-bar spring and type-bar-actuating connection to be a desirable one as regards the touch of the finger-piece and the behavior of the type-bar. The spring is preferably comparatively long, of 70 substantial diameter, and light tension. A materially greater tension will, however, be required where a key-lever is used, as in Fig. 6.

We claim as our invention—

1. In a writing-machine, the combination with the type-bar, of a type-bar-actuating connection having one end thereof operatively connected to the type-bar and its opposite end to a fixed part of the machine, 80 means causing such connection to be flexed at a point between the type-bar and such fixed part of the frame, and means acting to change the radius of the curve in which the point of flexure moves. 85
2. In a writing-machine, the combination with a platen and pivoted type-bar normally lying toward the front of the machine, of a flexing type-bar-actuating connection extending under the type-bar attached at its rear end thereto, at its front end to a fixed piece or part of a frame and capable of being flexed by power applied intermediate its ends and in rear of said fixed part and means acting to change the radius of the curve about which 95 the point of flexure moves, for the purpose set forth. 90
3. In a writing-machine, the combination with a platen and pivoted type-bar normally lying toward the front of the machine, of a flexing type-bar-actuating connection extending under the type-bar attached at its rear end thereto, at its front end to a fixed piece or part of a frame and capable of being flexed by power applied intermediate its ends and in rear of said fixed part, the part of the flexing connection in front of its point of flexure being capable of flexing and an abutment 100 against which said part strikes only during the latter stage of its movement, for the purpose set forth. 105
4. In a writing-machine, the combination of a platen and pivoted type-bar, of a flexing type-bar-actuating connection comprising two members united by a hinge-joint, the rear member being attached to the type-bar 110 and the front member being itself capable of flexure and attached to a fixed piece or part of the frame, means for depressing such flexing connection to throw the type-bar to the printing-point and an abutment located between the point of flexure and the fixed point against which said front member works, for the purpose set forth. 115
5. In a writing-machine, the combination of a platen and pivoted type-bar, of a flexing type-bar-actuating connection adapted to be flexed by power applied intermediate its ends and comprising two members one extending 120 from the point of flexure rearwardly to the 130

type-bar and the other forward to a fixed piece or part of the frame, the latter member being composed of links hinged together and an abutment against which said latter member works after the type-bar has made part of its excursion to the printing-point, for the purpose set forth.

6. In a writing-machine, the combination of a platen and type-bar pivoted in a plane below the platen and normally lying toward the front of the machine, with a flexing type-bar-actuating connection arranged under the type-bar, extending forwardly therefrom and connected at its rear end to the type-bar and at its front end to a fixed piece or part of the frame located in front of the head of the type-bar, means for acting upon such flexing connection intermediate its ends and in rear of said fixed part to pull the type-bar to the printing-point with an increasing velocity and a coiled spring having its rear end attached to the type-bar above or in front of its pivot and extending forwardly in the space between the type-bar and flexing connection,

25 the direction of movement of the flexing con-

nection being in opposition to the extension of the spring thereby affording a rapid retreat of the type-bar from the platen, substantially as and for the purpose set forth.

7. In a writing-machine, the combination 30 with a platen and pivoted type-bar normally lying toward the front of the machine, of a flexing type-bar-actuating connection extending under the type-bar and composed of two flexibly-connected members, a rear one 35 attached to the type-bar and the front one to a fixed piece in front of the head of the type-bar and having multiple pivots upon which it turns when the connection between the two members is flexed and the rear end of the 40 front one thereby depressed, for the purpose set forth.

In testimony whereof we have hereunto subscribed our names.

EDWARD B. HESS.
JOSEPH M. STOUGIITON.
